UNITED STATES PATENT OFFICE.

ADOLPH PETELER, OF FREEPORT, NEW YORK.

LIFTING-JACK WITH ROTATABLLE CAMS.

1,352,472.

Specification of Letters Patent. Patented Sept. 14, 1920.

Application filed August 22, 1919. Serial No. 319,088.

To all whom it may concern:

Be it known that I, ADOLPH PETELER, a citizen of the United States, residing at 147 Denhoff Avenue, Freeport, county of Nassau, 5 and State of New York, have invented certain new and useful Improvements in Lifting-Jacks with Rotatable Cams, fully described and represented in the following specification and the accompanying drawings, forming a part of the same.

The present invention relates to a lifting jack having a rack upon the edge of the lifting-bar, a lifting-pawl pivoted to a lifting-lever, and a holding-pawl for retaining the 15 lifting-bar when elevated step by step by the lifting-pawl.

The object of the invention is to furnish means constructed with a small number of parts for actuating the lifting-pawl and 20 the holding-pawl so as to lift the lifting-bar at pleasure, to lower it step by step, or to clear both pawls from the rack so that the lifting-bar may be raised or lowered to any extent in a single movement.

25 These objects are attained by projecting a stud from one side of each pawl, and pivoting a rotatable cam upon the casing of the jack adjacent to each pawl, the cam being formed of flat sheet-metal with an eccentric edge between its pivot and the said pawl, and the cams being linked to one another by a slotted connection, and connected by a spring which presses them normally in the same direction, to hold both pawls in an inoperative position, which permits the lifting-bar to be raised and lowered by hand.

The operation of the invention will be understood by reference to the annexed drawing, in which Figure 1 is a side elevation of 40 the jack with the cover A to the gear-box removed; Fig. 2 is an edge view of the same with the socket for the lifting-lever broken off close to the casing; Fig. 2^a is a section on line 3—3 in Fig. 1; and Fig. 3 is a section of 45 the same in section on line v—v in Fig. 5. Fig. 4 is a diagram showing the position of the parts adapted, when no load is upon the lifting-bar, to drop the entire lifting-bar by raising and lowering the lifting-lever; and 50 Fig. 5 is a diagram showing the parts dis-

posed for lowering the lifting-bar step by step.

a designates the lifting-bar formed with a rack of teeth a' upon one edge.

Fig. 1 shows a casing b in which the lifting-bar is moved and which, as shown in Fig. 2, is formed upon one side with a housing which contains a chamber c at one edge of the casing, and a chamber c' at one side of the casing, with a partition d between the 55 two chambers.

The holding-pawl or detent e is pivoted upon the partition in the upper part of the chamber c by a pivot n, and the socket f for the lifting-lever is pivoted in the bottom of the chamber upon a fulcrum g, and has the lifting-pawl e' pivoted to a pin g' upon its inner end.

The pivot n for the detent e extends through the outer wall of the casing and the 65 partition d into the chamber c' where it forms a fulcrum for a wire-spring having leaves or free ends z, z' applied to the outer sides of studs x—x' upon the pawls to press them normally toward the rack to engage its 70 teeth a'. This pivot n has a head n' to retain the coil of the wire spring in place, and the pivot is a little larger in the chamber c' than where it crosses the chamber c, thus forming a shoulder to hold the head n' at a 75 fixed distance from the partition.

A stud x is projected from the pawl e through an opening or slot v' in the partition, to be actuated by a cam h in the chamber c', and a corresponding stud x' is extended from the pawl e' through an opening v' in the partition, to be actuated by a cam i.

These cams are formed, as shown in Figs. 1 and 3, of flat sheet-metal, which permits them 90 to be stamped accurately to the desired form at the lowest possible cost, and are pivoted respectively upon pivots u and u'.

The pivot n of the holding-pawl e is fixed, and the cam h has an eccentric edge between 95 its pivot and the stud x, which operates to press the pawl e out of the rack when the cam is turned upward.

The two cams are connected by a link j attached to them farther from the fulcrums 100

of the cams than their eccentric edges, the link being jointed to a pin *l* upon the plate of the cam *h*, and its lower end being furnished with a pin *l* which is fitted to a slot 5 *m* in the plate of the lower cam.

The plate of the lower cam *i* is extended beyond the slot *m* to form a finger-piece *p*, by which the lower cam may be set in two different positions in which it engages 10 respectively stops *p'* and *p''*, shown in Fig. 1, upon the side of the chamber *c'*.

Lever-arms *q* and *q'* upon the cam-plates are extended reversely from the pivots *u* and 15 *u'* of the two cams and connected by a coiled spring *r* which operates to press the two cams in the same direction; that is, upwardly toward the studs upon the respective pawls, and with sufficient force to cause the retraction 20 of the pawl *e'* from the rack when the latter is not loaded.

The cams are provided to force the pawls away from the teeth *a'* in lowering the rack, which in the case of the holding-pawl *e* is effected by turning the eccentric edge of the 25 cam against the stud *x* of the pawl, as shown in Fig. 4.

In the case of the lifting-pawl *e'* the withdrawal is effected by locking the cam (by means of the finger *p*) in position to intercept 30 the stud *x'* of that pawl when it is moved downward by the lifting-lever.

The operation of the parts is as follows:

When the finger *p* is engaged with the lower stop *p'* it stretches or extends the 35 spring *r*, and its tension draws the cam *h* forcibly upward and draws the pivot *l* upwardly in the slot *m*, as shown in Fig. 1.

In this adjustment of the parts, the oscillation 40 of the hand-lever through its entire range of movement effects the lifting of the lifting-bar step by step, the cams clearing the studs *x* and *x'* and having no effect upon the pawls.

The holding-pawl *e* therefore slips over 45 each tooth as the lifting-pawl elevates the lifting-bar, and engages the following tooth while the lifting-pawl is lowered.

With the finger *p* raised into contact with the upper stop *p''*, as in Fig. 4, the lifting-bar may, if loaded, be lowered step by step, as the load upon the lifting-bar holds the lifting-pawl in engagement with the nearest tooth, so that it cannot be forced out of the teeth by the action of the cam *i*.

As the stud *x'* descends under such conditions it pushes the cam and its finger *p* downwardly, and also draws the cam *h* downward by the link-connection thereto, as shown in Fig. 5. This permits the spring *z* to press 60 the pawl *e* into the rack as each tooth is lowered.

With a similar disposition of the parts, the lifting of the hand-lever, when the lifting-bar is not loaded, wholly releases the lifting-bar, as it causes the spring *r* to raise the cam

h, as shown in Fig. 4, to retract the pawl *e*, and also draws the stud *x'* into contact with the cam-face *i*, so that the lifting-pawl *e'* is also retracted, as shown in Fig. 5.

It will be understood that the spring *z* or 70 *z'* does not exert a sufficient pressure to move the pawls into the teeth of the rack when opposed by the cams, and that the cams are held in their working position only, by the coiled spring *r*. Such spring exerts force 75 enough to hold the cams (when in operation) so that they may retract the pawls in opposition to the pressure of the wire-spring *z*, *z'*.

In brief, the lifting-bar is raised step by step by pulling the cams downward, as shown 80 in Fig. 1, so that for the time they become inoperative.

To lower the lifting-bar when loaded, the finger *p* of the lower cam is raised to the stop *p''*, thus bringing the cams into operative relation; but the load on the lifting-bar and lifting-pawl preventing the cam *i* from retracting such pawl. The same disposition of the parts, if the lifting-bar be unloaded, permits the clearing of the pawl entirely 90 from the lifting-bar by the mere lifting of the hand-lever, as the cam *i* operates to retract the lifting-pawl from the rack when the hand-lever is lifted.

Having thus set forth the nature of the invention what is claimed herein is:

1. A lifting jack having a lifting-pawl and a holding-pawl with a stud upon one side of each pawl, a rotatable cam pivoted adjacent to each pawl with an eccentric edge 100 adapted, when turned upon its pivot, to draw the pawl out of the rack, and an extension-finger integral with one of the cams for moving the cams and locking them in an operative or inoperative position.

2. A lifting jack having a lifting-pawl and a holding-pawl with a stud upon one side of each pawl, a rotatable cam pivoted adjacent to each pawl with an eccentric edge adapted, when turned upon its pivot, to draw 110 the pawl out of the rack, a link having a slotted connection with the cams, and a finger extended from one of the cams for holding the cams in either an operative or inoperative position.

3. A lifting jack having a lifting pawl and a holding pawl with a stud upon one side of each pawl, a rotatable cam pivoted adjacent to each pawl with an eccentric edge adapted to draw the pawl out of the rack, 120 and a single spring connecting the cams and operating to hold them normally in a pawl-shifting position.

4. A lifting jack having a lifting-pawl and a holding-pawl with a stud upon the side 125 of each pawl, a rotatable cam pivoted adjacent to each pawl with an eccentric edge adapted to draw the pawl out of the rack, lever-arms extended reversely from the pivots of the cams, and a spring connecting 130

the said arms and operating to hold the pawls in an operative position.

5. A lifting jack having a lifting-pawl and a holding-pawl with a stud upon one side of each pawl, a cam pivoted adjacent to each pawl and formed of flat metal with an eccentric edge adjacent to the pivot to bear upon a pawl-stud, links connecting the cams

at points farther from their pivots than the eccentric edges, a spring connected to the cams and pressing them normally in the same direction, and a finger for moving and locking the cams.

In testimony whereof I have hereunto set my hand.

ADOLPH PETELER.
